UNITED STATES PATENT OFFICE.

JEPHTHA W. HUNTER, OF MOUNT STERLING, ILLINOIS, ASSIGNOR OF ONE-HALF TO WHITE WASHBURN, OF SAME PLACE.

WHIFFLETREE.

SPECIFICATION forming part of Letters Patent No. 672,856, dated April 23, 1901.

Application filed January 15, 1901. Serial No. 43,381. (No model.)

To all whom it may concern:

Be it known that I, JEPHTHA W. HUNTER, a citizen of the United States, residing at Mount Sterling, in the county of Brown and 5 State of Illinois, have invented a certain new and useful Whiffletree, of which the following is a specification, reference being had therein to the accompanying drawings.

This invention relates to whiffletrees; and 10 the object in view is to provide a whiffletree of such construction that the strain or draft will be distributed on the cross-bar of the shafts or thills at points equidistant from the center thereof and adjacent to the junction 15 of the cross-bar with the thills or shafts, as contradistinguished from the ordinary whiffletree, which is centrally connected pivotally to the center of the cross-bar.

The invention contemplates the use of a 20 pair of elbow-levers pivotally mounted at a considerable distance from each other and operatively connected by means of a rod which has associated therewith antirattler-springs.

The invention also contemplates novel 25 means for mounting and journaling the elbow-levers and holding the same in place on the cross-bar of the thills.

Other objects and advantages of the invention will appear in the course of the ensuing 30 description.

The invention consists in certain novel features and details of construction and arrangement of parts, as hereinafter fully described, illustrated in the drawings, and pointed out 35 in the claims.

In the accompanying drawings, Figure 1 is a plan view showing the improved whiffletree applied to the cross-bar of a pair of shafts or thills. Fig. 2 is an enlarged detail vertical 40 section taken longitudinally of one end of the cross-bar and showing the interlocking means on the contiguous faces of one of the elbow-levers and bearing-plate, also showing the keeper and taper pin. Fig. 3 is a plan view 45 of the bearing-plate. Fig. 4 is a bottom plan view of one of the elbow-levers. Fig. 5 is a bottom plan view of one of the keepers. Fig. 6 is a detail vertical section showing the relation between one of the elbow-levers and the 50 connecting-rod and the antirattler-spring, &c.

Similar numerals of reference designate cor-

responding parts in all the figures of the drawings.

In the drawings, 1 designates the cross-bar of a pair of shafts or thills 2, the said parts 55 being of the usual construction and the shafts or thills being provided at their heel ends with eyes 3 to receive the usual thill-couplings.

In carrying out the present invention I employ a pair of elbow-levers 4, each of which comprises a long arm 5 and a short arm 6. Normally the arms are arranged as shown in Fig. 1, the long arms 5 extending in opposite directions and away from each other and the 65 short arms 6 extending rearward in a substantially parallel relation to each other. The short arm of each elbow-lever is provided at its extremity with a depending spring-cap 7, which is substantially cylindrical in form, 70 as best illustrated in Figs. 4 and 6, and which forms a housing for an antirattler-spring 8. The two elbow-levers are operatively connected by means of a rod 9, having angular end portions forming depending terminal pintles 10, which pass downward through openings 11 in the short arms 6 of the elbow-levers and into and through the caps 7. Each of the pintles 10 is encircled by a coiled spring 80, which is housed within the cap 7 and which is seated at one end against the inner wall 12 of the cap, which wall is in reality the end portion of the short arm 6 of the elbow-lever. A washer 13 is placed on the pintle 10 and held in place by means of a fastening-pin 14, 85 inserted through an opening extending transversely of the pintle, adjacent to its extremity. The washer 13 is arranged at a short distance from the lower edge of the cap 7, so as to allow for play, and said washer forms a spring- 90 seat against which the outer or lower end of the antirattler-spring 8 bears.

By the means just described the terminal pintles of the connecting-rod are held in engagement with the short arms of the elbow-levers and the end portions of the connecting-rod are held firmly seated against the upper sides of the short arms of the elbow-levers, thus preventing any rattling at the joints between the connecting-rod and the elbow- 100 levers.

Each of the elbow-levers 4 comprises a disk-

- shaped elbow 15, comprising an outer annular flange 16 and an inner annular flange 17, surrounding a central opening 18, which is tapered, as illustrated in Figs. 2 and 4, to fit snugly around a tapered boss 19, extending upward from the center of a bearing-plate 20. The base-plate 20 is also of disk form and provided with oppositely-extending attaching-ears 21, having openings 22 to receive suitable fasteners 23, by means of which the bearing-plate is secured to the cross-bar 1, as illustrated in Fig. 2. The bearing-plate 20 also comprises an annular flange 24, of slightly less diameter than the annular flange 16 of the elbow-lever, which flange 24 is encircled by the flange 16 when the parts are assembled, as shown in Fig. 2. Within the flange 24 the upper surface of the bearing-plate 20 is dished to form a cup 25, adapted to contain suitable lubricating material, which is thereby supplied to the interfitting parts of the elbow-lever and bearing-plate. A securing-bolt or pivot-pin 26 passes through a central opening 27 in the bearing-plate 20 and like openings in the keeper 28 and cross-bar 1, the head of the bolt resting upon the keeper, as shown in Fig. 2, and the lower end of the bolt being held by a retaining-nut. The bolt 26 forms the central pivotal connection between the elbow-lever and bearing-plate.
- Associated with the elbow-lever and bearing-plate is a keeper comprising a flat body portion 28, which overlies the elbow-lever and is provided with a laterally-extending arm or securing portion 29, provided with openings to receive suitable fasteners 30 and also provided in its under side with a recess 31 to receive and interlock with the adjacent ear 21 of the bearing-plate, as shown in Fig. 2.
- From the foregoing description it will be seen that the elbow-levers are operatively connected by means of a rod which has associated therewith antirattler-springs, so arranged as to prevent any rattling of the joints between the connecting-rod and elbow-levers. It will also be seen that the elbow-levers are so mounted that they are comprised between metal bearing-plates and keepers, so that there is no chance for the elbow-levers to

wear against the wooden cross-bar. It will further be seen that the strain brought to bear on the elbow-levers is not transmitted to a single pivot pin or bolt, but that the elbow-levers and their bearing-plates have interlocking or interfitting parts which distribute the strain and wear and remove the same from the pivots or bolts; also, that provision is made for lubricating the interfitting parts of the elbow-levers and bearing-plates. 55

I do not desire to be limited to the exact details of construction and arrangement of parts hereinabove set forth and accordingly reserve the right to change, modify, or vary the construction within the scope of this invention. 60

Having thus described the invention, what is claimed as new, and desired to be secured by Letters Patent, is—

1. A whiffletree composed of a pair of elbow-levers, corresponding arms of which have pendent spring-caps, a connecting-rod having terminal pintles extending downward into the caps, antirattler-springs housed within the caps and associated with the pintles, 70 and means for fastening the springs in place, substantially as described.

2. A whiffletree comprising a pair of elbow-levers connected for simultaneous movement, bearing-plates upon which said levers are 80 mounted, interlocking flanges on the meeting faces of the levers and plates, and a keeper associated with each elbow-lever and having an interlocked engagement with the bearing-plate, substantially as described. 85

3. A whiffletree comprising a pair of operatively-connected elbow-levers, bearing-plates having oppositely-projecting attaching-ears, interlocking flanges on the meeting faces of the levers and plates, and keepers associated with the elbow-levers and provided with recesses to receive the attaching-ears of the bearing-plates, substantially as set forth. 90

In testimony whereof I affix my signature in presence of two witnesses.

JEPHTHA W. HUNTER.
